UNITED STATES PATENT OFFICE

137,736

DESIGN FOR A COMBINATION BABY BATH TABLE AND DRESSING STAND

Katherine H. Morrey, Chicago, Ill.

Application September 15, 1943, Serial No. 111,132

Term of patent 14 years

(Cl. D33—14)

To all whom it may concern:

Be it known that I, Katherine H. Morrey, a citizen of the United States, residing at Chicago, in the county of Cook and State of Illinois, have invented a new, original, and ornamental Design for a Combination Baby Bath Table and Dressing Stand, of which the following is a specification, reference being made to the accompanying drawings, forming a part thereof, in which:

Fig. 1 is a perspective view of a combination baby bath table and dressing stand, showing my new design, the baby bath table being illustrated in its normal inwardly recessed position;

Fig. 2 is a front elevational view thereof;

Fig. 3 is an end elevational view of the article as seen from the left-hand end of Fig. 2, the baby bath table being illustrated in its outwardly extended position of use;

Fig. 4 is an end elevational view as seen from the right-hand end of Fig. 2; and

Fig. 5 is a top plan view of the article as illustrated in Fig. 3.

I claim:

The ornamental design for a combination baby bath table and dressing stand, substantially as shown and described.

KATHERINE H. MORREY.
